UNITED STATES PATENT OFFICE.

HARRY A. CLARK, OF WICHITA FALLS, TEXAS.

STROKE-LENGTH ADJUSTMENT FOR WALKING BEAMS.

Application filed March 19, 1926. Serial No. 96,046.

This invention relates to the art of drilling wells and more particularly to an improvement in the spudding attachment of combination drilling and clean-out machines, the primary object being to provide through a novel arrangement, a means to alter the length of stroke of such an attachment to obtain results of added efficiency when working in mud and other formations of varied 10 construction.

The invention further comprehends in an attachment such as designated above, an arrangement by which additional sets of jars may be utilized, due to the extra long stroke 15 available, for spudding, cleaning out and numerous other purposes.

With these and other novel objects and advantages in view the invention has particular reference to certain features of construction and assembly of parts by which 20 said objects are attained and which will be manifested in the course of the following detail description and illustrated in the appended drawings, wherein:

25 Figure 1 represents an elevational view of an improved, portable drilling and clean-out machine upon which the invention is especially applicable.

Figure 2 represents a detail view of the 30 main power wheel, depicting the adjustable relationship of the spudding arm pitman and the walking beam pitman.

Figure 3 is a similar view in cross-section, and

35 Figure 4 represents a pair of plates arranged to be situated on opposing sides of the spudding arm pitman at the point of pivotal engagement of the walking beam pitman.

40 In referring more in detail to the drawings, particular attention is directed to the Figure 1, in which is illustrated a specially constructed combination machine, equipped with facilities for general use in the oil field.

45 The machine is provided with a collapsible mast 1, a walking beam 2 pivotally disposed upon the top of the upright 3, likewise a set of spudding arms 4, having pivotal engagement with a shaft 5 at the rear of the machine frame.

50 Spudding and cleaning out operations have hereto been severely handicapped through the absence of proper stroke adjustments, and while adjustments may be made in the stroke, these adjustments are usually

of such limited scope as to be of little consequence in so far as noticeable results are concerned.

The present invention proposes to improve the mechanism affecting the walking beam 2 and spudding arm 4, whereby these elements will co-act to produce a stroke, approximately, from 20 inches to eight feet, thus adding materially to the efficiency obtained in the operations aforesaid, and especially in mixing heavy formations with water for bailing, and jarring loose stuck drill stems, casing or other parts which may become wedged in the well.

The spudding arms 4 are provided with a connection to the power wheel 6 of the machine, in the form of a pitman 7. This pitman as apparent in Figure 1, is connected to a crank arm 8 which in turn is secured to and arranged to be rotated by the said wheel 6 and is provided with a series of apertures 9 for the adjustment of the pivotal engagement of the arm 7 along the radius of the wheel. The pitman 7 is further provided with a series of aligned apertures 10 whose purpose will presently be disclosed.

The walking beam pitman 11 is pivotally suspended where its lower end may be secured by a suitable bolt 12, as in Figure 3 especially, in one of the series of apertures 10, depending upon the length of stroke desired. Plates 13, or their equivalents as in Figure 4, may be placed on opposing sides of the pitman 7, to afford proper protection against frictional wear.

Now, power supplied by the motor 14 to rotate the wheel 6, is also imparted to the drilling drum 15, likewise in transporting the machine from place to place. A line 16 is secured to the drum 15, about a sheave 17 situated upon the shaft 5 at the rear of the machine, thence about a sheave 18 on the spudding arm 4, after which it passes over a sheave 19 in the head of the mast 1. A small roller or sheave 20 is mounted adjacent the base of the mast as shown, and receives the line 16, after which the latter is passed about a sheave 21 in the temper screw 22, depending from the walking beam 2, thence into the well. Through such an assembly, it is apparent that many stroke adjustments may be obtained, to effect the movement of either the walking beam or spudding arms, the latter being adjusted by moving the lower pivotal point of the arm 7 along the

apertures 9 in the arm 8, and while this adjustment may affect the stroke of the walking beam 2, the pivotal point of the arm 11 may be moved to a higher point in the apertures 10 in the arm 7 to overcome the reduced stroke length resulting from the former adjustment. In addition to the described adjustments, the usual stroke adjustment through the temper screw 22 remains 10 unaltered.

The added advantage in this long stroke attachment is apparent in that positive control of the lines as maintained at all times, the line being lengthened as required by rotating the drum 15 to play off, by releasing the brake on the drum, and the surplus assumed when proper depth is attained by the action of the spudding arms 4.

In jarring operations, the brake of the drum 15 may be released to permit jars attached to the end of the line 16 to fall into the well, and likewise in this regard, considerable saving in time and expense is realized in repeated jarring operations due 25 to the extended long stroke.

It should be understood that the invention has been described as including all of the elements set forth in the appended claims, but that certain changes and modifications may be resorted to without departing from the spirit or intent of the invention.

I claim—

1. The combination including with the walking beam and spudding arm of a combination drilling and clean-out machine; a pitman connected to said spudding arm and to the power wheel of said machine, having apertures alined therein, a second pitman 40 having its upper end secured to said walking beam; and means to permit pivotal engagement of the lower end of said latter pitman with a selected one of the apertures of said first pitman, to alter the stroke length 45 of said walking beam:

2. The combination including with the walking beam and spudding arms of a portable drilling and clean-out machine; apertured arms having adjustable pivotal engagement along the radius of the power wheel of said machine and pivotally secured to said spudding arms to impart rocking movement to said latter element; a second arm depending from the end of said walking beam; and means on the lower end of said latter arm to permit of pivotal securing in a selected one of the apertures in said

first arm, in accordance with the required distance of travel of said walking beam.

3. In a stroke length adjustment for the walking beam and spudding arms of a combination drilling and clean-out machine; a pitman detachably connected to the power wheel of said machine and to said spudding arms to impart motion thereto; said pitman provided with a multiplicity of spaced apertures; a second pitman arranged to have one of its ends secured to said walking beam, and means to pivotally mount its lower end to a selected one of the apertures of said first pitman, to extend motion to said walking beam.

4. In a stroke length adjustment for the walking beam and spudding arms of a combination drilling and clean-out machine, an apertured member arranged to communicate motion to said spudding arms from the power wheel of said machine; an arm pivotally secured to said walking beam and to said first member and arranged to transmit the motion of said member to said walking beam, and means to alter the connections of said arms to increase or decrease the stroke length of said walking beam and spudding arms.

5. In a stroke length adjustment for the walking beam and spudding arms of a drilling and clean-out machine; means to impart co-ordinate rocking motion to said elements, said means including an arm pivoted to said spudding arms and in the radius of the power wheel of said machine; a second arm pivoted intermediate the ends of said first arm, and means to move the second arm with respect to its pivotal engagements with said first arm to alter the stroke of said walking beams.

6. In a combination drilling and clean-out machine a stroke length adjustment for the walking beam and spudding arms thereof including a pair of arms arranged to impart rocking motion to said elements, one of which is detachably pivoted in the radius of the power wheel of said machine and to said spudding arms, the other of said arms arranged to be pivoted intermediate the ends of said first arm to extend the motion thereof to said walking beam, and means to move said pivotal engagement to predetermined points along the length of said first arm to increase or decrease the extent of motion imparted to said walking beam.

In testimony whereof I affix my signature.
HARRY A. CLARK.
